UNITED STATES PATENT OFFICE

158,119

WEIGHT BOX

Carl Louis Otto, New York, N. Y., assignor to The
Torsion Balance Company, New York, N. Y., a
corporation of New York

Application May 26, 1948, Serial No. 146,618

Term of patent 14 years

(Cl. D58—12.6)

To all whom it may concern:

Be it known that I, Carl Louis Otto, a citizen of the United States of America, residing in the Borough of Manhattan, city, county, and State of New York, have invented a new, original, and ornamental Design for a Weight Box, of which the following is a specification, reference being had to the accompanying drawings, forming part thereof, wherein—

Figure 1 is a top plan view of a weight box, showing my new design, with the lid open,

Fig. 2 is a front elevation of the weight box shown in Fig. 1, with the lid closed.

Fig. 3 is a section taken substantially along the plane of the broken line 3—3 of Fig. 1.

Fig. 4 is a section taken substantially along the plane of the broken line 4—4 of Fig. 1.

I claim:

The ornamental design for a weight box as shown.

CARL LOUIS OTTO.
